UNITED STATES PATENT OFFICE.

GEORGE A. JENNER, OF SAN ANTONIO, TEXAS.

NUMBER-DISPLAYING DEVICE.

1,107,525.

Specification of Letters Patent. Patented Aug. 18, 1914.

Application filed January 27, 1913. Serial No. 744,526.

To all whom it may concern:

Be it known that I, GEORGE A. JENNER, a citizen of the United States, residing at San Antonio, in the county of Bexar and State of Texas, have invented certain new and useful Improvements in Number-Displaying Devices; and I do declare the following to be a full, clear, and exact description of the invention, such as will enable others skilled in the art to which it appertains to make and use the same.

This invention relates to improvements in illuminated signs and particularly to illuminated number displaying devices for vehicles.

One object of the invention is to provide a device of this character having an improved construction and arrangement of number holding frame and reflector casing whereby the sign and reflector are protected and automatically cleaned of dirt from within, and which may be applied to the tail or side light of a vehicle, and said light employed for illuminating the number or sign.

Another object is to provide a peculiar disposition of the reflectors so that the light shining from the lamp will pass along the length of the casing, then be thrown back obliquely onto the rear reflectors, and by them be deflected forward onto the number plate.

Another object is to provide a device of this character which will be simple, strong, durable and inexpensive in construction, efficient in operation and well adapted to the purpose for which it is designed.

With these and other objects in view, the invention consists of certain novel features of construction, and the combination and arrangement of parts as will be more fully described and claimed.

In the accompanying drawings: Figure 1 is a perspective view of a vehicle lamp showing the invention applied thereto; Fig. 2 is a detail perspective view of the reflector casing and a sign holding frame with the sign removed; Fig. 3 is a vertical cross sectional view of the reflector casing and sign holding frame and through the reflector and sign plates therein; Fig. 4 is an enlarged longitudinal section of the inner end of the reflector casing showing more clearly the means for holding the reflectors in position therein; Fig. 5 is a detail plan view of the reflector casing showing more clearly the

construction of the outer end thereof; Fig. 6 is a detail perspective view of the mirror holding bar which fastens the inner edges of the mirror in the casing; Fig. 7 is a perspective view of a slightly modified form of the mirror casing and sign holding frame showing the latter hinged at its upper edge to the mirror casing.

In the embodiment of the invention, I provide a mirror casing 1 which is preferably triangular in cross section or has its rear walls or sides inclined from their front edges toward the center of the rear side of the casing as shown. The open front side 70 of the casing is preferably of rectangular oblong shape and the inner end 2 of the casing is triangular and has therein a light opening 3 which is surrounded by a longitudinally extending tapered socket 4 adapted to be engaged with and secured over an opening in one side of a lamp 5 as clearly shown in Fig. 1 of the drawings. The opposite or outer end 6 of the mirror casing is rearwardly and outwardly inclined.

Arranged in and suitably secured to the inner surfaces of the inclined rear sides of the casing are reflecting plates 7 which are preferably in the form of glass mirrors or may be constructed of any suitable material capable of receiving and maintaining a high polish. The mirror plates 7 at their front edges are supported and fastened in position in the casing by hook shaped clips 8 which are soldered or otherwise rigidly secured 90 to the inner surfaces of the rear sides of the casing, and at their rear edges the plates 7 are fastened in position by a longitudinally disposed angle iron bar 9 having therein slots 10 which, when the bar 9 is placed 95 in position against the outer surfaces of the inner edges of the mirror plates, receive fastening loops or staples 11 which are secured to the inner surfaces of the corner formed by the engaging rear ends of the rear sides 100 of the casing as clearly shown in Fig. 3 of the drawings. The looped outer ends of the staples 11 project a slight distance beyond the bar 9, and engaged with said looped ends of the staples are angular keys 12 105 which lock the bar 9 in place to support the inner ends of the mirror plates.

It will be noted that the mirror plates terminate a short distance from the inner end of the casing, thus obviating any danger of 110 the heat from the lamp cracking or the smoke blacking the mirror plates. In order

to hold the mirror plates 7 against longitudinal movement in the casing which would be permitted by constructing the mirrors of less length than the casing, the bar 9 has 5 formed on the end thereof adjacent to the inner ends of the mirror plates offset inwardly extending stop lugs 13 which engage the inner ends of the mirror plates 7 as clearly shown in Fig. 4 of the drawings 10 and thus hold the plates against longitudinal movement in the casing. Engaged with the rearwardly and outwardly inclined outer end of the casing is a triangular end mirror or reflecting plate 14 which, owing 15 to its angle to the axis of the casing, reflects the light entering the casing through the opening 3, back onto the mirror plates 7 on the rear sides of the casing whence it is thrown onto the sign or number plate 15 20 covering the front open side of the reflector casing.

The number plate 15 may be of any suitable material but is preferably a glass plate 25 painted or suitably colored to form an opaque or dark background which surrounds the numbers or other characters. The latter may be painted in light colors so as to be readily observed in the day time against the dark background or to be illuminated 30 at night by the light reflected therethrough from within the mirror casing, but I do not wish to be confined in this respect and by the term "number plate" as used herein I desire 35 to be understood as covering any member of plate shape bearing any kind of characters which are visible by day or night.

The number plate 15 may be secured or supported in position over the front open side of the casing in any suitable manner, 40 said plate being preferably engaged with a channel shaped frame 16 which may be formed integral with or rigidly secured to the front edges of the reflector casing as shown in Figs. 2 and 3 of the drawings in 45 which instance the upper end of the frame is omitted and the number plate adapted to be slipped downwardly in the channel shaped sides of the frame and into engagement with the lower bar thereof whereby 50 the number plate is firmly but removably held in position over the front open side of the reflector casing.

In Fig. 7 of the drawing is shown a slightly different form and arrangement of 55 number plate supporting frame 17. In this instance the frame 17 is hingedly secured to the upper front edge of the reflector casing and is adapted to be swung upwardly to an open position as is indicated in Fig. 60 7 of the drawings. When swung downwardly to a closed position the frame 17 may be fastened by a spring catch 18 or in any other suitable manner.

Attention is directed to the fact that with 65 the construction shown in Fig. 1 where the

number plate rises vertically, as well as with the construction shown in Fig. 7 where the number plate is hinged along its upper edge, any dirt which accumulates within the interior of the casing will tend to fall out 70 of it because the lower wall of the reflector is inclined toward the front. It will automatically jiggle out behind the hinged door, and if it accumulates along the bottom of the fixed number plate shown in Fig. 1 the 75 plate may be lifted a little from time to time. It is well known to those who have used lamps of this kind that soot as well as dirt accumulates within the lamp so that the numbers as well as the mirrors or reflectors become fogged, and this also will 80 fall out as described or at least will accumulate below the line of the numbers.

By constructing and arranging my improved number displaying device as herein shown and described it will be seen that the number may be readily seen in the day time as well as at night and by arranging the reflectors as herein shown and described the latter may be readily removed when 90 broken or injured and new reflector plates substituted therefor.

From the foregoing description taken in connection with the accompanying drawings, the construction and operation of the 95 invention will be readily understood without requiring a more extended explanation.

Various changes in the form, proportion and the minor details of construction may be resorted to without departing from the 100 principle or sacrificing any of the advantages of the invention as claimed.

Having thus described my invention, what I claim is:

1. In a number displaying device, a pair 105 of rectangular reflectors with their rear edges standing substantially in contact on a horizontal line and their bodies diverging from each other forward of said line, and an outer triangular reflector whose rear edges are substantially in contact with the outer ends of the other reflectors and whose front edge stands flush with their front edges, its body standing in a plane oblique to said line; combined with a metallic casing inclosing 110 and supporting said reflectors and having means for admitting light at that end opposite the outer reflector, and a light-pervious number plate carried by said casing and standing normally across the front edges of 115 all reflectors.

2. A number displaying device comprising a casing triangular in cross section and having an opening at its inner end adapted to admit light from a lamp, an upright light- 125 pervious number plate covering its front, rear walls converging toward each other from the upper and lower edges of the front, an outer end wall whose body inclines outward from said front toward the rear at an 130

angle to the axis of said casing and whose rear edges unite with the outer ends of said rear walls, and reflectors on the inner faces of the end and rear walls, for the purpose set forth.

3. In a number displaying device, the combination with a metallic casing substantially triangular in cross section and having an open front and converging rear walls, a reflector adjacent the inner face of its outer end wall, and a socket opening through its inner end wall and adapted to admit light from a lamp; of a light-pervious number plate over the open front of said casing, and reflectors secured to the inner faces of said rear walls and extending from the outer end wall to a point near to but spaced from the inner end of the casing, for the purpose set forth.
4. In a number displaying device, the combination with a casing of substantially triangular cross section having a closed outer end and an opening through its inner end adapted to admit light from a lamp, and a light-pervious number plate covering the open front of the casing; of clips projecting from adjacent the front edges of the converging rear walls of said casing, loops projecting from the angle between these walls, an angular strip having slots passing over said loops, keys through said loops removably holding the strip in place, and mirror plates each secured at its rear edge by said strip and at its front edge by a pair of said clips.
5. In a number displaying device, the combination with a casing of substantially triangular cross section having a closed outer end and an opening through its inner end adapted to admit light from a lamp, and a light-pervious number plate covering the open front of the casing; of clips projecting from adjacent the front edges of the converging rear walls of said casing, loops projecting from the angle between these walls, an angular strip having slots passing over said loops and stop lugs at its inner end,

keys through said loops removably holding the strip in place, and mirror plates each secured at its rear edge by said strip and at its front edge by a pair of said clips and with its inner end resting against one of said stop lugs and spaced a slight distance from the inner end of the casing.

6. In a number displaying device, the combination with a casing of substantially triangular cross section having a closed outer end and an opening through its inner end adapted to admit light from a lamp, and a light-pervious number plate covering the open front of the casing; of clips projecting from adjacent the front edges of the converging rear walls of said casing, loops projecting from the angle between these walls, an angular strip having slots passing over said loops, keys through said loops removably holding the strip in place, and mirror plates each secured at its rear edge by said strip and at its front edge by a pair of said clips.

In testimony whereof I have hereunto set my hand in presence of two subscribing witnesses.

GEORGE A. JENNER.
